ALTERNATING CURRENT RELAY

Oscar A. Ross, New York, N. Y., assignor to General Railway Signal Company, Rochester, N. Y.

Original application November 14, 1925, Serial No. 69,130. Divided and this application September 25, 1930, Serial No. 484,414

3 Claims. (Cl. 175—294)

This invention relates to relays, and more particularly to that class of relays known as signaling relays employing alternating current for their operation.

5 This application is a division of application Ser. No. 69,130, filed November 14, 1925.

One object is to provide means for automatically heating the interior of a relay during periods of extremely cold weather when lowered temperatures might cause interference with the proper operation of said relay. In localities where the outside temperature seldom reaches zero for any length of time the heat dissipated by the energized windings of relays used for rail-way signal control or for track circuits or the like is sufficient to maintain the interior chambers of such relays sufficiently high to avoid a freezing of any moisture which may have gathered therein due to condensation or the like and thus avoid freezing of such moisture which might cause a failure of the signals on the side of danger, by giving a clear signal when dangerous traffic conditions exist.

However when such relays are operated in colder localities where sub-zero temperatures are encountered for long periods of time, there is insufficient heat dissipated by operation of the relay to safeguard against freezing of moisture and resulting danger of false clear indications. It is therefore desirable to provide additional heating means, controlled so that they are in operation only when additional heat is required.

A further object of the invention is to provide automatic cut-out means which will prevent operation of the relay motor, should the ambient temperature become dangerously low, either due to the heating means being inoperative, or due to the heating means being ineffective to maintain a proper temperature because of unusually low outside temperatures.

Other objects and advantages will appear as the description of the invention progresses, and the novel features of the invention will be pointed out in the appended claims.

45 This invention consists in the novel construction and arrangement of parts hereinafter described, delineated in the accompanying drawings, and particularly pointed out in that portion of the instrument wherein patentable novelty is claimed for certain and peculiar features of the device, it being understood that, within the scope of what hereinafter thus is claimed, divers changes in the form, proportions size and minor 50 details of the structure may be made without de-

parting from the spirit of the invention, or sacrificing any of the details.

In describing the invention in detail, reference is had to the accompanying drawings, wherein I have illustrated one embodiment of my invention 60 and wherein like characters of reference designate corresponding parts throughout the several views, and in which:

Fig. 1 is an elevational front view of the preferred form of my invention;

Fig. 2 is a top view, with what is known as the contacting mechanism removed to show the interior of the relay;

Fig. 3 is a part sectional, part elevational view taken on the line A—A of Fig. 1;

Fig. 4, shows, diagrammatically, heating means for the relay;

The relay comprises two general units, one the contacting mechanism, and the other the motor movement and case.

The contacting mechanism comprises insulation plate 4, secured by screws 41 and depending from which are bearing brackets 5 and 6, pivotally mounted in which is contact bar 7, having trunnions 8 and 9, at each end and circuit closing devices, or contacts as 10 and 11 mounted on opposite parallel sides thereof. Said contacting devices 10 and 11, are more fully described in my co-pending application for Letters Patent Serial Number 65,399, filed October 28, 1925, suitable means, (not shown) serving to hold said contacts to said bar. Also secured to bar 7, by screws 38—38 is arm 37, carrying counter-weight 39 adjustably secured by screw 40. Circuit controlling device 10 is generally known as a front contact and its terminals are connected to the rear binding posts 16 and 17, by metal extensions 18 and 19, and flexible conductors 20 and 21, passing through insulated guide strip 22. Circuit controlling device 11, is generally known as the back contact and its terminals are connected to front binding posts 23 and 24 through metal extensions 25 and 26, and cables 27 and 28, also passing through guide strip 22. Binding posts 29—29 are four in number and form the terminals for the windings on the stators of the relay motor, conductors 32, 33, 35 and 36 connecting to said posts. Binding posts 30, form the terminals for thermostat 31, of any well known construction and the terminals of which are placed in the circuit of one of the stator windings, preferably the phase having the lower inductance, as for example the track phase of a track relay. Also attached to contact bar 7, by screws 42—42, is lever 43, said lever being the 100

105

110

division point between aforesaid contact unit 2, and motor unit.

Motor unit 3, comprises molded metal frame, or case 44, the four vertical sides of which are enclosed by doors 45, 46, 47 and 48, secured by screws 49—49 and contain transparent sheets 50—50, preferably of glass set in said doors with plastic cement and are held in place by the clamping effect of screws 49—49, a pliable gasket 51—51, 10 serving to prevent dust or other foreign matter from entering the relay interior.

Also forming part of case 44, are machined lugs, or projections 60—60, rigidly secured in which are studs 61—61 acting to locate stator 62, preferably termed a core, with respect to stator 53, nuts 65—65 securing said core in place. Core 62, comprises lamina 63 and 64, bracket 66, containing bearing 67 adapted to guide the upper end 15 of shaft 69 being clamped between said stator, or core 62 and nuts 65.

Rotor 68, comprises shaft 69, to which is rigidly secured flanged support 70, carrying metal rotor shell 71, secured by rivets 72—72, and has the lower end of shaft 69 stepped in bearing 73, 25 more fully described in my co-pending application Serial Number 65,398 filed October 28, 1925, the upper end being guided by bearing 67, the protruding portion carrying lever 74, the outer end of which, is limited by stops 74a and 74b secured to stator, or core 62, and is pivotally connected to link 77 by screw 76, said link being also 30 pivotally connected to lever 43 by screw 43a. Pin 75 serves to secure lever 74 to shaft 69.

Incandescent lamps 78 and 79 adequately secured in case 44, and receiving energy from the source supplying the relay windings, are controlled by manually operated switch 80 for inspection purposes, and by thermostat 116, said thermostat acting to cut in said lamps upon a predetermined lowering of temperature within the case 44, said lamps thereafter acting to increase the temperature within said case.

The operation of my improved relay is as follows:—Figs. 1, 2, and 3, illustrate what is known in the art as a quick-acting two position relay. Energizing of windings on stator 62, causes rotor 68 to actuate lever 74 through the included angle H, moving from stop 74b, to stop 74a, this movement being known as picking up of the relay to the 45 front contact position, and, as said movement occurs, the circuit through contacts 10—10 will be closed and those through 11—11 will be opened, such opening and closing being more fully described in my co-pending application for Letters Patent Serial Number 65,399 filed October 28th, 1925. De-energizing of said windings will cause lever 74 to return to stop 74b, by action of counter-weight 39, said last named movement causing the circuits through contacts 10—10 to be 50 opened, and those through contacts 11—11 to be closed, this being known as dropping away to the back-contact position.

As shown in Figs. 1, 2, and 3, lever 74 is assumed to be traveling from stop 74b to stop 74a, the 55

several views showing the relation of the moving parts with said lever equi-distant said stops.

Further, by the novel arrangement of an automatically controlled heating unit inside the relay case, a substantially uniform temperature is 80 maintained therein, in this manner precluding any possibility of improper operation due to excessive lowered atmospheric temperatures outside the relay case.

Further, by the novel arrangement of an automatically controlled thermostat 117 in series with, and adjacent to, winding 35 of said relay, any extraordinary condition, as extreme weather, producing a temperature inside said relay case, so low that, the heat from the stator windings combined with that of the automatically controlled heating units, is not sufficient to maintain adequate heat, will cause said thermostat 117 to act to open the circuit in which it is placed, thereby calling attention to the extreme condition existing within said relay. Under ordinary operation such a condition is only established if one, or both of the heating units should burn out, whereafter no auxiliary heat could be supplied to the 90 relay interior.

Having described my invention, I now claim:—

1. An alternating current relay comprising a stator having a plurality of windings thereon, a magnetic core having an axis parallel to the axis of said stator and arranged to furnish an air gap 105 between said stator and said core, a non-magnetic metallic rotor positioned to operate in said air gap, contacting mechanism operated by said rotor, in combination with thermostatic means connected to so control at least one of said windings that said relay becomes inoperative upon a predetermined reduction in temperature of the atmosphere surrounding said relay.

2. In an alternating current relay, in combination, a stator having a plurality of windings adapted to be fed from a source of electrical energy, a rotor the operation of which is influenced by induction from said stator, contacting means actuated by said rotor, and a thermostat so connected in one of said windings that said rotor becomes inoperative to actuate said contacts upon a predetermined reduction of the temperature of the atmosphere surrounding said relay.

3. In an alternating current relay, a housing comprising a stator having a winding thereon adapted to be fed from a source of electrical energy, a rotor the operation of which is influenced by induction produced by said stator winding, contacting means operated by said rotor, a thermostat connected to make the rotor inoperative upon a predetermined reduction in the ambient temperature, a heating unit positioned to heat the interior of said housing, and thermostatic means operating to cut said heating unit into operation upon such a reduction of the atmospheric temperature within said housing as to endanger proper functioning of said relay.

OSCAR A. ROSS.
